CLAIM

The ornamental design for a table, as shown and described.

DESCRIPTION

FIG. 1 is a bottom, front, left perspective view of a table showing my new design;
FIG. 2 is a front view thereof;

FIG. 3 is a rear view thereof;

FIG. 4 is a left side view thereof;

FIG. 5 is a right side view thereof; and,

FIG. 6 is a bottom view thereof.

The broken lines showing the circular unshaded regions within the shaded area represent screw holes that form no part of the claimed design. The broken lines depicting the remainder of the table show features that form no part of the claimed design.

1 Claim, 6 Drawing Sheets(56)
